UNITED STATES PATENT OFFICE.

JOHN T. HANNON, OF NATICK, MASSACHUSETTS.

METAL PROTECTOR FOR BOOTS AND SHOES.

1,146,157.

Specification of Letters Patent. Patented July 13, 1915.

Application filed September 15, 1914. Serial No. 861,903.

To all whom it may concern:

Be it known that I, JOHN T. HANNON, a citizen of the United States, residing at Natick, in the county of Middlesex and State of Massachusetts, have invented new and useful Improvements in Metal Protectors for Boots and Shoes, of which the following is a specification.

This invention relates to a metal protector for the fore part of the sole of a boot or shoe which is particularly adapted to be used in connection with miners' and soldiers' boots and shoes where the soles and toe caps or tips of the shoes are exposed to very rough usage.

The object of the invention is to provide a protector which can be readily attached to the sole of a boot or shoe of ordinary construction and which will prevent the sole of the boot from being cut and worn by contact with the rough stone and ore with which said boots come in contact.

The object of the invention is further to provide a metal protector which will prevent the wearer from slipping.

The invention consists in a metal protector such as hereinafter described in the specification and particularly as set forth in the claim.

Referring to the drawings: Figure 1 is a plan view of my improved metal protector. Fig. 2 is a sectional elevation taken on line 2—2 of Fig. 1. Fig. 3 is a sectional elevation showing the protector attached to the sole of a boot or shoe.

Like numerals refer to like parts throughout the several views of the drawings.

In the drawings, 5 is the metal protector which is provided with a plurality of series of hollow conical projections 6 having closed ends. Said projections are struck up from the metal forming the tread portion of the protector and constitute a means for preventing the wearer from slipping, said projections 6 being formed upon the tread portion of the protector and projecting outwardly therefrom. Said protector is also provided with a plurality of pointed triangular projections 7 which are struck up from the metal of which the protector is formed between adjacent hollow conical projections 6 of the outer series of said projections and constitute a fastening means whereby said protector can be joined to the sole 8 of a boot or shoe. The protector is

also provided with a plurality of triangular projections 9 which, when the protector is first stamped out, appear as shown in dotted lines at the rear edge of the protector in Fig. 1, said triangular projections being subsequently bent up into the position illustrated in full lines in the drawings. Said projections 9 when driven into the sole of the shoe and clenched therein serve to rigidly fasten the extreme rear edge of said protector to the sole of the shoe. The projections 7 and 9 are driven through the sole 8 and clenched on the inner side thereof as shown in Fig. 3.

My improved protector is preferably formed of a single piece of sheet metal with the different projections hereinbefore described integral with the body portion of the protector. After the protector has been fastened to the shoe, the shoe is worn in the usual manner while the protector saves the sole of the shoe from abrasion and wear and also prevents the wearer from slipping.

The metal protector 5 is preferably provided with a plurality of holes 10 so that additional fastening means, such as nails, may be driven through these holes into the sole and assist in holding the protector to the sole.

Having thus described my invention, what I claim and desire by Letters Patent to secure is:

A protector of metal for the fore part of a boot or shoe comprising a tread portion constructed to cover substantially the whole of the fore part of the sole of a boot or shoe and with a plurality of series of hollow projections integral therewith and projecting outwardly therefrom and a plurality of pointed triangular projections struck up from said metal and projecting from the inner face thereof along the extreme rear edge of said protector and other triangular projections struck up from said metal between adjacent hollow projections of one of said series, whereby said protector may be fastened to the fore part of the sole of a boot or shoe.

In testimony whereof I have hereunto set my hand in presence of two subscribing witnesses.

JOHN T. HANNON.
